UNITED STATES PATENT OFFICE.

FRITZ MUSTER AND HANS MUSTER, OF RUEGSAU, SWITZERLAND.

TRANSPORTING CASE.

1,411,976.

Patented Apr. 4, 1922.

Application filed August 31, 1920. Serial No. 407,169.

To all whom it may concern:

Be it known that we, FRITZ MUSTER and HANS MUSTER, both citizens of the Republic of Switzerland, and residents of Ruegsau, 5 in the Canton of Berne, Switzerland, have invented certain new and useful Improvements in Transporting Cases, of which the following is a specification.

In transporting cases hitherto known and 10 chiefly used for the transport of substances in powder form, such as spice, chemicals and so forth, the body of the case is generally formed of a number of staves which are secured together by means of iron or steel 15 bands. Experience has shown, however, that these staves, usually made of veneer of beech-wood and consequently of a thickness of about 5 millimeters only, are easily subject to shrinkage especially after having 20 been in use for a considerable time, so that the transporting case becomes unretentive. It has been tried to avoid such drawback by constructing the body of the transporting 25 case of one single board and, by steaming the same, to give it a cylindrical shape which method had the disadvantage of being complicated and expensive.

It is the object of the present invention to eliminate these drawbacks, the novel 30 feature distinguishing our invention from known transporting cases consisting in that the main body or cylindrical board forming the sides of the case, which is in the shape of a wooden barrel, is provided at its inner and 35 outer face with a series of grooves the purpose thereof being hereinafter described.

In order that the invention may be fully understood, reference is made to the accompanying drawing, in which:

40 Fig. 1 shows an outside view, and

Fig. 2 a sectional elevation of the transporting case constructed in accordance with our method.

Fig. 3 illustrates a top view of part of 45 the board in straightened position.

The new transporting case comprises a main body in the form of a cylindrical board *a* representing the sides of the case, the inner as well as the outer face of said 50 board being provided with longitudinal grooves *b* in such a manner that, as will be more clearly seen from Fig. 3, the two sets of grooves are transposed in relation to each other. The portions interposed between 55 the grooves are hereby wider than the latter,

and the purpose of transposing the two sets of grooves is to enable the employment in the construction of transporting cases or staves for barrels of soft wood even when the same is knotted, a breakage owing to 60 this arrangement of the grooves being prevented. Provision is further made of rings *c* which, by any suitable means (not shown) are secured to the said main body and made to embrace it at the top and bottom and 65 centre part respectively.

This transporting case is particularly adapted for use in conveying substances such as spice in powder form and is provided at the inner face with a lining *d* of paste board 70 having undulations made to fit in the aforesaid grooves. The body or board *a* is fashioned at the top and bottom with a butment *e* having shoulders at *f* and the ends of the lining *d* are bent outwardly in such a manner that they are made to rest against the 75 said shoulders. In order to retain these outwardly bent portions or flanges in their position, that is in the position shown in Fig. 2, in which the lining is caused to fit 80 tightly against the inner face of the body or board *a*, the latter has annular recesses at *g* forming a continuation of the shoulders *f* into which recesses the flanges of the lining *d* are pressed. The inner face of each of 85 the butments *e* is slightly slanting and serves to receive a lid *i* having a paste board lining *h* of which the outer edge abuts against the flange of the lining *d*. In this way the 90 whole of the interior of the transporting case is limited by linings which render the case air-tight and prevent the goods to be transported to come in contact with wood or iron and acquire their odour.

The safeguarding of the lids *i* is effected 95 in the known manner, for instance by means of a ring *k* driven into the slanting face of the butment *e* and against the lid. The ends of the lining *d* could, if desired and for the sake of simplicity, be made to terminate at and lie flush with the shoulders *f* of the butment in which case, however, other means would have to be provided to secure the lining to the body *a* of the transporting case.

We are aware that it is not new in transporting cases or staves for barrels, tubs and the like, to provide the same with corrugations or grooves at the inner side in order 100 to increase the area of the wood surface and 105 110

facilitate carbonization in the case of liquor to be aged, or to corrugate the barrel stave at one side for other purposes.

What we claim as new and desire to secure 5 by Letters Patent is:

A transporting case of substantially cylindrical form having a series of symmetrically disposed grooves at its inner and outer faces running in the direction of the wood as it 10 grew, the said inner and outer grooves being transposed in relation to one another and the portions interposed between the neigh-

boring grooves being wider than said grooves, substantially as and for the purpose set forth.

15

In testimony whereof we have hereunto set our hands in the presence of two subscribing witnesses.

FRITZ MUSTER.
HANS MUSTER.
